George A. Young,

George A. Young

Attorneys

UNITED STATES PATENT OFFICE.

GEORGE A. YOUNG, OF DETROIT, MICHIGAN, ASSIGNOR TO YOUNG BROTHERS COMPANY, OF DETROIT, MICHIGAN, A CORPORATION OF MICHIGAN.

OVEN PANEL.

Application filed January 15, 1923. Serial No. 612,875.

To all whom it may concern:

Be it known that I, GEORGE A. YOUNG, a citizen of the United States of America, residing at Detroit, in the county of Wayne and State of Michigan, have invented certain new and useful Improvements in Oven Panels, of which the following is a specification, reference being had therein to the accompanying drawings.

This invention relates to oven panels and has special reference to insulating panels that may be used as doors, partitions and walls of ovens and other structures, and the invention relates to that class of panels which are fabricated from metal and insulation material in contradistinction to insulating wall boards or blocks devoid of enclosures.

One of the objects of my invention is to provide a metallic panel that can be filled with a powdered or granular insulating material and such material maintained in place without any danger of the material settling, packing or becoming displaced to the extent of forming crevices or air pockets which would reduce the insulating characteristics of the panel.

Another object of this invention is to furnish a hollow metallic panel with interior reinforcing members that will serve two purposes; first, that of bracing and lending rigidity to the walls of the panel, and second, that of providing interior shelves or supports for insulating material within the panel. The arrangement of shelves or supports is such that they do not interfere with a continuous insulation of the panel from one end thereof to the other end from one side to the other and in all directions, nor does the arrangement interfere with equal distribution of the insulation material within the panel.

A further object of this invention is to provide an insulating panel in which one hundred per cent of cheap and raw insulating material may be used in powdered or granular form, the insulating material being compressed within the panel to eliminate air gaps or any spaces that will afford loss of heat.

A still further object of this invention is to provide a strong and durable fabricated panel that will withstand a high degree of heat, and the construction entering into the

panel will be hereinafter specifically described and then claimed.

Reference will now be had to the drawing, wherein—

Figure 1 is a front elevation of a portion of the panel in accordance with my invention;

Fig. 2 is a vertical sectional view taken on the line II—II of Fig. 1, and

Fig. 3 is an enlarged horizontal sectional view taken on the line III—III of Fig. 1.

An oven panel in accordance with this invention comprises flat parallel sheet metal front and rear walls 1 and 2, top and bottom walls 3 and 4, and side walls 5, the walls 3, 4 and 5 being channel shaped in cross section with the flanges 6 thereof outstanding against the inner faces of the walls 1 and 2 so that the marginal edges of the walls 1 and 2 may be inturned over the flanges 6 and spot welded or otherwise connected to said flanges. All the walls cooperate in forming a flat rectangular enclosure or casing, and the side walls 5 may be reinforced against buckling, by plates 7 set against the inner faces of the walls. In many instances it is not necessary to use such reinforcing plates.

The top and bottom walls 3 and 4, intermediate the ends thereof may be provided with angle reinforcing members 8 connecting the walls 3 and 4 to either the wall 2 or the wall 1, and in some instances the reinforcing members 8 may be dispensed with.

Mounted on the inner faces of the walls 1 and 2, preferably by spot welding, are transversely disposed alternately arranged angle bars 9 having short flanges secured to the walls 1 and 2 and long flanges projecting into the space between the walls 1 and 2 to serve functionally as shelves or supports within the casing or enclosure formed by the walls 1 to 5 inclusive.

In the panel casing or enclosure is placed an insulating material 10. This insulating material is preferably powdered or granular in order that raw material, plentiful and practically waste, may be used, and we use one hundred per cent of this material in contradistinction to insulating blocks or fillers using about seventy-five per cent insulating material, and the remainder lime and asbestos fibre or other binders. The powdered or granular insulating material

is compressed in the panel enclosure to provide a solid, more or less homogeneous mass within the panel. The insulating material being compressed about the angle bars 9 provides an insulation throughout the panel for the reason that the angle bars are staggered; do not contact, and afford a sinuous insulating path from one end of the panel to the other. When the panel is used in a vertical position there is no danger of the insulating material settling or packing in the bottom of the panel, which has been the objectionable feature of insulating powder for oven panels.

15 I do not care to confine my invention, unless necessary, to a powdered insulating material as a plastic insulating material may be employed, for instance a material that could be poured into the panel through a suitable opening to harden within the panel and exclude air from the panel. Therefore one embodiment of my invention has been described, but it is to be understood that changes may be made without departing from the scope of the appended claims.

What I claim is:—

1. A panel of the class described, comprising

ing a metallic enclosure having opposed flat walls, an insulating material within said enclosure, and means on the flat opposed walls of said enclosure and alternately disposed therein for preventing settling or packing of the insulating material in one part of said enclosure.

2. A panel of the class described, comprising a metallic enclosure, inwardly projecting supports carried by walls of said enclosure with the supports of one wall spaced from the supports of an adjacent wall, and a homogeneous mass of insulating material in said metallic enclosure on and between the supports therein.

3. An oven panel comprising metallic walls forming an enclosure, reinforcing members on the inner faces of some of said walls with some of said reinforcing members serving as supports, said reinforcing members affording a sinuous space from one end of said panel to the opposite end thereof, and insulating material in the sinuous space of said panel and on the reinforcing members serving as supports.

In testimony whereof I affix my signature.
GEORGE A. YOUNG.
